CLAIM

We claim the ornamental design for food product, as shown.

DESCRIPTION

FIG. 1 is a perspective view of a food product, according to the present invention;

FIG. 2 is a top plan view of the food product of FIG. 1;

FIG. 3 is a bottom plan view of the food product of FIG. 1;

FIG. 4 is a side elevation view of the food product of FIG. 1, focusing on one point of five points contained therein; and,

FIG. 5 is a side elevation view of the food product of FIG. 1, from between two points.
